MEAT-SLITTING MACHINE

Joseph P. Spang, Quincy, Mass., assignor to Cube Steak Machine Company, Inc., Boston, Mass., a corporation of Massachusetts

Application December 3, 1937, Serial No. 177,957

6 Claims. (Cl. 17—25)

This invention relates to meat-slitting machine having a set of rotary slitting knives and in which the meat to be slit is supported on a meat-supporting table that is separable and detachable from the machine, and is adapted to be introduced into the machine at one side of the set of knives and to be fed through the machine beneath the knives, which thereby operate to slit the meat, and is further adapted to be discharged 10 or removed from the machine at the other side of the knives.

In the operation of a meat-slitting machine of this type it is desirable that the meat-supporting plate with the slice of meat thereon should be 15 fed through the machine at a speed slower than the peripheral speed of the knives so that the latter will operate on the slice of meat with a draw cut.

It is one of the objects of my present invention 20 to provide novel means for thus feeding or controlling the movement of the meat-supporting plate through the machine.

In the drawings wherein I have illustrated some 25 embodiments of my invention,

Fig. 1 is a vertical sectional view through a meat-slitting machine embodying my invention;

Fig. 2 is a fragmentary plan view of the plate-feeding means;

Fig. 3 is a perspective view on a reduced scale 30 showing the under side of the meat-supporting plate;

Fig. 4 is a view similar to Fig. 1 but showing a different embodiment of the invention;

Fig. 5 is a fragmentary plan view of the plate- 35 feeding means shown in Fig. 4;

Fig. 6 is a section on the line 6—6, Fig. 5;

Fig. 7 is a fragmentary sectional view showing still a different embodiment of the invention;

Fig. 8 is a perspective view of the plate-feed- 40 ing means illustrated in Fig. 7;

Fig. 9 is a bottomside view of the meat-sup- 45 porting plate shown in Fig. 7;

Fig. 10 is a fragmentary view showing the means for adjusting the conveyer frame of Fig. 4.

Referring first to Fig. 1, 1 indicates the frame 50 of the machine which is provided with a hollow or chambered base portion 2 adapted to house a motor 3 by which the knives are operated. Rising from each end of the frame is a standard 55 or end member, one of which is shown at 4 in Fig. 1. These upstanding end members 4 provide a bearing for the knife shaft 5 on which is mounted a plurality of slitting knives 6. The knife shaft 4 is shown as provided with a pulley 7 which is connected by a belt 8 to a pulley 9

on the motor shaft. The knives are thus rotated by the motor in the direction of the arrow, Fig. 1. 10 indicates a cover or guard member which is supported on the uprights 4 and which covers and protects the knives 6.

11 indicates a meat-supporting plate which is separable and detachable from the machine and which supports the slice 12 of meat which is to be slit during the slitting operation. In the operation of the machine the plate 11 with the slice 10

12 of meat thereon is introduced into the machine at one side thereof (the right side in Fig. 1) and is passed through the machine beneath the knives, the knives thereby operating to cut slits in the meat, and is then discharged from the machine at the other side thereof with the slit slice of meat thereon. The first pass of the plate through the machine will cut a series of parallel slits in the meat, and if it is desired to cut a second series of slits in the meat crossing those 20 of the first series then the plate with the partially slit meat thereon is again introduced into the machine at the right-hand side thereof but in such a position that the first series of slits which were cut in the meat are extending at 25 right angles to the direction of feed, and the plate is then passed through the machine a second time with the result that a second series of slits will be cut in the meat at right angles to the slits of the first series. After the plate has 30 been discharged it may be removed with the slit slice of meat thereon.

13 indicates fragmentarily a spring finger stripper member which engages the meat as it is being acted on by the knives and serves to hold the 35 meat against the plate and prevent it from being lifted therefrom by the knives.

The parts thus far described may have substantially the same construction as that illustrated in my co-pending application Serial No. 40 91,676, filed July 21, 1936.

In using a meat-slitting machine of this type it is very desirable that the knives should act on the meat with a draw cut in order to make clean 45 cut slits, and, as stated above, the present invention relates to novel means for controlling the feeding movement of the plate 11 so that the meat will be fed beneath the knives at a slower speed than the peripheral speed of the knives. This is accomplished herein by providing the 50 machine with a plate-conveying device which positively moves the plate through the machine at a predetermined speed that is less than the peripheral speed of the knives. This conveyer may be constructed in various ways without de- 55

parting from the invention. In Fig. 1 I have shown an endless conveyer 14 in the form of an endless apron which passes around two rolls 15, 16. The rolls 15 and 16 are journalled in and carried by a conveyer frame indicated generally at 17 and which comprises two angle-iron side rails 18 that are suitably connected together and which are situated on either side of the endless apron 14.

10 The roll 15 is positively driven and it serves to give the feeding movement to the upper run of the conveyer 14. Although any appreciable way of rotating the roll 15 may be employed I have shown herein a simple mechanism by which 15 said roll is rotated from the knife shaft 5. The shaft 23 of the roll 15 has fast thereon a gear 19 which meshes with a gear 20 on the knife shaft 5. The gear 19 has a considerably larger diameter than that of the roll 15 and as the 20 gears 19 and 20 have about the same diameter the surface speed of the roll 15, and hence the speed of feeding movement of the upper run of the conveyer 14, will be much slower than the peripheral speed of the knives 6.

25 The endless conveyer 14 and the meat-supporting plate 11 are constructed to have an interlocking engagement so that when the plate has been placed on the right-hand end of the conveyer the latter will positively feed the plate 30 forward beneath the knives at the same speed as that of the conveyer.

In Figs. 1 and 3 the meat-supporting plate 11 is shown as having a projection 21 depending from its under side and the conveyer has a plurality of apertures 22 adapted to receive said projection 21. In the operation of the device the operator merely places the plate 11 with its slice 12 of meat thereon on the right-hand end of the continuously moving conveyer, and as 40 soon as one of the apertures 22 comes into register with the projection 21 the latter will enter the aperture as shown in Fig. 1, this providing the interlocking engagement between the conveyer and the plate. The movement of the 45 upper run of the conveyer in the direction of the arrow b moves the plate positively beneath the knives, thereby making slits in the meat, and as the feeding movement of the plate is slower than the peripheral speed of the knives the latter will act on the meat with the desired draw cut.

The meat-supporting plate is shown as square and has a diametrical dimension such that the edges of the plate will rest on the horizontal legs of the angle-iron members 18 of the conveyer frame 17 as shown in Fig. 2 wherein the plate 11 is indicated in dotted lines. These angle-iron members 18 extend somewhat beyond the conveyer at the discharge end (the left-hand end in Figs. 1 and 2) and hence after the plate 60 11 has been fed past the knives, and as it reaches the left-hand end of the conveyer, said plate is fed onto the extended portions of the rails 18 as shown by dotted lines, Fig. 1. As the 65 portion of the conveyer having the aperture 22 therein passes around the roll 15 the plate will be automatically disengaged from the conveyer and will remain on the extended portions of the rails 18. The roll 15 has the portion 91 of reduced diameter in the path of travel of the pin 70 21 so as to avoid any engagement of said pin with the roll during the feeding movement of the plate 11. After the plate has been delivered to the extended portions of the rails 18, the operator may then remove the plate from the rails 75 for the purpose of again placing it into the ma-

chine at the right-hand side in order to make the second set of slits in the meat at right angles to those of the first set, and when the plate has made its second pass through the machine with the meat thereon, then it and the slit slice of 5 meat carried thereby may be removed from the extended portion of the rails 18.

The conveyer frame 17 is preferably made adjustable in a vertical direction so as to provide for varying the depth of the slits which are cut 10 in the meat. As shown in Fig. 1 the shaft 23 of the roll 15 is journalled in the uprights 4 at the ends of the frame and the conveyer frame 17 is mounted so that it can be turned about the shaft 23 as an axis. At the right-hand end of 15 the conveyer frame the rails 18 are connected by a yoke 24 which extends around the conveyer belt. This yoke carries an adjustable screw 25 which engages a cam member 26 pivotally mounted on the frame at 27, said cam being 20 provided with a handle 28 by which it may be turned. By turning this cam the right-hand end 25 of the conveyer frame may be raised or lowered, said frame turning about the shaft 23 as an axis during the rising or falling movement. This 25 provides a simple device for giving vertical adjustment to the conveyer.

In Figs. 7 and 8 I have shown an endless belt conveyer having a slightly different construction from that shown in Figs. 1 and 2. In said Figs. 30 7 and 8 the endless conveyer belt is indicated at 14a and it passes around the rolls 15 and 16 as illustrated in Figs. 1 and 2, the roll 15 being the driven roll. The conveyer belt 14a, however, is provided with a plurality of ribs 30 which 35 extend transversely thereof, and the meat-supporting plate 11a is provided on its under side with a plurality of depending pins or projections 21a which are adapted to be engaged by the ribs 30 as seen in Fig. 7, thereby providing the interlocking engagement between the plate and the conveyer.

These ribs 30 may be provided for in various ways, and as herein illustrated the conveyer apron 14a has secured to it a plurality of angle-shaped members, one leg of each of which rests on and is secured to the apron 14a and the other leg of which provides the rib 30.

In Figs. 4, 5 and 6 I have illustrated an embodiment of the invention in which the conveyer 50 is in the form of a roller conveyer rather than an endless belt conveyer. In this embodiment of the invention the conveyer frame is indicated at 17a and it comprises two connected side rails 18a which extend between the upright portions 4 55 of the frame. Carried by these rails 18 are a series of positively driven conveyer rolls 33, 47 which support the meat-supporting plate 11b and feed it past the knives 6. Conveyer rolls 33, 47 are shown as being driven from the knife shaft 60 5, for which purpose said shaft has a gear 34 thereon which meshes with and drives a gear 35 on the shaft 36 of the roll 47, and the other conveyer rolls 33 are shown as connected to the driven roll 47 by means of a sprocket chain drive. 65 In Fig. 4 the shaft 36 of the roll 47 extends into and is journalled in the upright portions 4 of the frame and said shaft has the gear 35 fast thereon. The shaft 36 of roll 47 is also provided with a sprocket wheel 37 which drives a sprocket chain 70 39 that has engagement with the sprocket wheels 38 carried by the shafts of each of the other conveyer rolls 33.

The conveyer frame 17 is thus pivotally mounted in the machine on the shaft 36 and 75

means are provided for adjusting said frame about the shaft 36 to raise and lower the conveyer relative to the knives 6. The two rails 18a of the conveyer frame are connected by a cross piece 40 which carries an L-shaped member 41, the horizontal arm 42 of which extends into a cam slot 43 formed in a cam member 44 that is pivotally mounted at 45 to the frame. This cam member 44 has the handle 46 by which it may 10 be turned and the turning movement thereof will produce a movement of the conveyer frame about the shaft 36 at an axis by which the depth of the slits cut in the meat can be controlled. This cam 44 also serves to hold the conveyer 15 frame in its adjusted position.

The conveyer roll 47 at the entering end is shown as provided with portions 48 of rubber which provide a frictional engagement with the under side of the plate 11b, and I will preferably 20 employ presser rolls 49 to act on the upper face of the plate 11b at its edges in order to maintain a firm contact between said plate and the rubber surface 48 of the feed roll. These presser rolls 49, there being one at each end of the conveyer 25 roll 47, are shown as mounted on studs 50 which are supported in extensions 51 with which the rails 18a of the conveyer frame are provided. In using the device illustrated in Figs. 4 and 6 the meat-supporting plate 11b with the slice 12 of 30 meat thereon is placed on the right-hand end of the conveyer frame and is fed into position between the conveyer roll 47 and the presser rolls 49. The frictional engagement of the rubber portion 48 of the conveyer rolls 47 with the 35 plate 11b feeds the latter forwardly at a speed which is less than the peripheral speed of the knives so that the latter act on the meat with a draw cut. As the plate moves forward it is engaged by the other conveyer rolls 33 which continue the feeding movement of the plate, and when the plate is discharged from the rolls 33 it passes onto horizontal flanges 52 extending inwardly from the extended portions of the rails 18a of the conveyer frame.

In order to assist in holding the meat on the meat-supporting plate I propose to provide said plate with a plurality of apertures 53 which extend entirely through the plate. When the meat is resting on the apertured plate and is pressed 45 against it by the stripper member 13 the meat will be crowded into the apertures 53 somewhat thereby forming a sort of interlocking connection between the meat and the plate which will prevent the meat from slipping off from the plate 50 during the meat-slitting operation.

I claim:

1. A meat-slitting machine comprising a set 55 of rotary knives, means to rotate the knives, a meat-supporting plate separable from the machine and adapted to support the slice of meat to be slit, a pivotally mounted conveyor frame adapted to have a bodily swinging movement about its pivotal axis, a conveyor nonadjustably mounted on said conveyor frame and adapted to receive said plate and convey it past the knives, and conveyor-operating means which operate to actuate the conveyor in any adjusted position of the conveyor frame.

2. A meat-slitting machine comprising a set 60 of rotary knives, means to rotate the knives, a pivotally mounted conveyor frame capable of

having bodily swinging movement about its pivotal axis, for adjusting the frame toward and from the knives, a conveyor nonadjustably mounted on the conveyor frame and adapted to convey a slice of meat past the knives, and driving connections between the knives and conveyor for operating the latter, said driving connections being operative in all adjusted positions of the conveyor frame about its pivotal axis.

3. A meat-slitting machine comprising a machine frame, a set of knives rotatably mounted thereon, means to rotate the knives, a shaft carried by the frame parallel to the knife axis, a conveyor frame pivotally mounted on said shaft 10 to swing toward and from the knives, a conveyor nonadjustably mounted on said conveyor frame and adapted to carry the slice of meat to be slit past the knives, a drive roll on said shaft for operating the conveyor, driving connections between said shaft and the knives, and means for adjusting the conveyor frame about its pivotal axis.

4. A meat-slitting machine comprising a machine frame, a set of knives rotatably mounted 15 thereon, means to rotate the knives, a shaft carried by the frame parallel to the knife axis, a conveyor frame pivotally mounted on said shaft to swing toward and from the knives, an endless conveyor nonadjustably mounted on said conveyor frame and adapted to carry the slice of meat to be slit past the knives, a drive roll on said shaft for operating the conveyor, driving connections between said shaft and the knives, and means for adjusting the conveyor frame 20 about its pivotal axis.

5. A meat-slitting machine comprising a machine frame, a set of rotary knives mounted thereon, means to rotate the knives, a rotatable shaft mounted in the frame and extending parallel to the axis of the knives, a conveyor frame pivotally mounted on said shaft, an endless conveyor mounted on said conveyor frame, a feed roll on said shaft for actuating said conveyor, a meat-supporting plate separable from the machine and adapted to support the slice to be slit, said plate being adapted also to be fed past the knives by the conveyor, a projection depending from said plate and having interlocking engagement with the conveyor, driving connections between the knives and said shaft, and means to adjust the conveyor frame about its pivotal axis, thereby to vary the depth of the slits made in the meat.

6. A meat-slitting machine comprising a machine frame, a set of rotary knives mounted thereon, means to rotate the knives, a rotatable shaft mounted in the frame and extending parallel to the axis of the knives, a conveyor frame pivotally mounted on said shaft, a roller conveyor on said conveyor frame comprising a series of rolls and driving connections between said rolls and said shaft by which the rolls are positively rotated from the shaft, driving connections between said shaft and the knives by which 45 the shaft is rotated from the knives, and means to adjust the conveyor frame about its pivotal axis, thereby to vary the depth of the slits made in the meat.
